Alfred Fornander,
By his Attorney, John C. Seifert

UNITED STATES PATENT OFFICE.

ALFRED FORNANDER, OF NEW YORK, N. Y.

LOCKING DEVICE FOR TELEPHONES.

1,056,655.

Specification of Letters Patent. Patented Mar. 18, 1913.

Application filed July 11, 1912. Serial No. 708,835.

To all whom it may concern:

Be it known that I, ALFRED FORNANDER, a subject of the King of Sweden, residing in the borough of Manhattan, in the city, 5 county, and State of New York, have invented new and useful Improvements in Locking Devices for Telephones, of which the following is a specification.

This invention relates to telephones, and 10 particularly to means to lock the telephone to prevent the unauthorized use thereof, and it is the object of the invention to provide a device of this character which is cheap in construction, readily applicable to and 15 movable from all telephone apparatus, and efficient in operation.

With this object in view, I provide a locking device to be applied to the transmitter supporting column of the ordinary telephone apparatus, comprising a pair of pivotally connected or hinged members having 20 semi-circular portions to conform to and engage around the column with parallel arms projecting from such portions, one of the 25 arms having a hook to engage with the receiver-supporting lever to maintain it in its lower position; one of the arms has a key manipulable lock fixed thereto, the bolt of which coöperates with a flange or lip on the 30 other arm to releasably maintain the device in operative position on the column.

In the drawing accompanying and forming a part of this specification, Figure 1 is a perspective view of a telephone apparatus 35 with an embodiment of my invention applied thereto. Fig. 2 is a perspective view of my improved device, illustrating the same in its opened position; and Fig. 3 is a plan view, partly broken away to illustrate 40 the manner of locking the members together.

Similar characters of reference designate like parts throughout the different views of the drawing.

In the embodiment of my invention illustrated in the drawing, I have shown the same applied to the ordinary "desk set" telephone apparatus, comprising a supporting standard or column 4 for the transmitter 5, a receiver-supporting hook or lever 50 switch 6 projecting through a slot 7 in the column and pivotally supported therein, the slot being of such length as to permit of the raising of the lever in order to make the necessary electrical connection to use the telephone. The lever has the usual tines 8 in

which the receiver 18 is supported and having the usual openings 9 and normally maintained in its lower or disconnected position by the weight of the receiver, said lever being raised by the usual spring when the receiver is removed to make the necessary electrical connection. 60

My improved device relates to means to lock the lever 6 in its lower position and thereby preventing the making of the necessary electrical connection to use the telephone, and comprises a pair of members 10, 11, pivotally connected or hinged together, as at 12, the members 10 and 11 being constructed to conform to and adapted to engage around the column 5, as clearly shown in Fig. 1. One of the members, as 10, has a projecting arm 13 to extend parallel with and below the receiver lever 6 and has a laterally projecting hook 14 at the upper forward edge which is adapted to engage over the lever, in the present instance engaging in an opening in a lever tine 8. Also fixed to the inner face of the arm 13 is a lock 15 having a spring bolt 16 and operable by a removable key 17. The other member 11 also has an arm 19 to project forward parallel with the arm 13 having flanges 20, 21 at its upper and lower edges to inclose the top and bottom of the lock. The forward 70 end is bent up to form a flange with a lip 22 to inclose the front of the lock and in back of the lip of which the bolt 16 engages to lock the members 10 and 11 together. These flanges 75 20, 21 and 22 when the device is in position 80 on the column 4 preventing any tampering 85 with the lock.

When it is desired to place the device in position on the column to lock the telephone apparatus against use, the hook 14 is placed 90 in an opening in the lever and the members 10, 11 placed around the column 4, a slight pressure on the arms 13, 19 causing the spring bolt to engage in back of the lip 22 locking the device in position on the 95 column, the hook 14 preventing any upward movement of the lever 6. To remove the device it is only necessary to insert the key into the lock and release the lock bolt when the arm 19 will be freed to swing on its 100 hinge 12 and the hook 14 is lifted out of the opening 9.

It will be noted that the members engaging around the column are so constructed as to engage below the annular flange formed 110

by the connection of the transmitter to the column preventing any upward movement of the device on the column.

Variations may be resorted to within the scope of my invention.

Having thus described my invention, I claim:

1. In a telephone apparatus, the combination with the transmitter-supporting column and receiver hook pivotally supported thereby, of a pair of hinged members to engage the column and having a portion to engage over the receiver hook, and a lock operable by a removable key to lock said members to the column, substantially as and for the purpose specified.
2. In a telephone apparatus, the combination with the transmitter-supporting column and receiver hook pivotally supported thereby, of a pair of pivotally connected members to engage the column having parallel arms, one of the arms having a portion to engage over the receiver hook, and a lock operable by a removable key fixed to one arm and coöperating with the other arm to lock the members to the column, substantially as and for the purpose specified.
3. In a telephone apparatus, the combination with the transmitter-supporting column and receiver hook pivotally supported there-

by, of a pair of hinged members to engage the column having parallel arms, one of the arms having a hook to engage over the receiver hook; a lock fixed to the inner face of one of the arms; and lateral flanges on the other arm to engage over the lock having a lip with which the bolt of the lock coöperates to lock the members to the column, substantially as and for the purpose specified.

4. In a telephone apparatus, the combination with the transmitter supporting column and switch lever having receiver-supporting tines with openings therein, of a pair of pivotally connected members to engage the column and having integral parallel arms; a hook at the upper forward edge of one arm to engage in an opening in one of the receiver-supporting tines; a lock fixed to the inner face of one of said arms having a bolt operable by a removable key; lateral flanges on the other arm to engage over the edges of the lock, one of which flanges is formed with a lip in back of which the bolt of the lock is adapted to engage to secure the members together, substantially as and for the purpose specified.

ALFRED FORNANDER.
